UNITED STATES PATENT OFFICE.

EUGENE I. POWERS AND HENRY C. HIX, OF PITTSBURG, KANSAS; SAID POWERS AS SIGNOR TO SAID HIX.

PNEUMATIC LIFT JACK.

Application filed January 25, 1923. Serial No. 614,859.

To all whom it may concern:

Be it known that EUGENE I. POWERS and HENRY C. Hix, citizens of the United States, residing at Pittsburg, in the county of 5 Crawford and State of Kansas, have invented certain new and useful Improvements in Pneumatic Lift Jacks, of which the following is a specification.

This invention relates to new and useful 10 improvements in lifting jacks and more particularly to a pneumatic device of this character and the primary object is to provide a jack which is designed to be operated by fluid pressure, such as water, air 15 or other fluid under pressure.

A further object of the invention resides in the provision of a simple device of the above mentioned character which may be connected, if desired with the air pump of 20 an automobile so that when applied to a particular machine it may be effectively used in connection with the motor of that same machine.

A still further object of the invention is 25 to provide a lifting jack of the above mentioned character, which is provided with means whereby a sufficient quantity of air may be taken from one of the tires of the motor vehicles when it is desired to use the 30 jack upon the same and furthermore when an air pump is not at hand.

A still further object of the invention is to provide a lifting jack of the above mentioned character, which is simple in construction, inexpensive, strong, durable and well adapted for the purpose for which it is designated.

Other objects and advantages of this invention will become apparent during the 40 course of the following description.

In the accompanying drawings forming a part of this specification and in which like numerals designate like parts throughout the same:—

45 Figure 1 is a side elevation of the device constructed in accordance with my invention.

Figure 2 is a top plan view thereof.

Figure 3 is a vertical section therethrough and

50 Figure 4 is a transverse section taken on lines 4—4 of Fig. 3.

Fig. 5 is a detail.

In the drawings, wherein for the purpose of illustration is shown the preferred embodiment of my invention, the numerals 55 1 and 2 designate telescoping cylindrical members and operating within the inner cylindrical member 2 is a piston 13, the rod of said piston being designated by the 60 numeral 3. The outer cylinder 1 has a base plate 4 which is provided with an inlet port 5 adjacent one end thereof and is more clearly shown in Fig. 1 of the drawings and this inlet port 5 communicates with a conduit 6 formed in the base 4 to permit the air or other fluid under pressure to enter the interior of the cylinder 1. The base plate 4 is furthermore provided with an integral projection arranged centrally 70 upon the upper face of the base plate 4 through which the conduit 6 extends and this projection 7 constitutes a proper bumper for the cylinder 2. The cylinder 1 is also provided with an annular top 75 flange 8 and said annular top flange and base plate 4 are held together by means of suitable tie rods 9.

The base of the inner cylinder 2 is integral with the walls thereof and is provided with a plurality of fluid inlet ports 80 10. The outer face of the base of this cylinder 2 carries a suitable leather gasket 11 and secured to the underface of this gasket 11 is a pad or other covering of soft 85 material as shown at 11' in the drawings so as to prevent undue shock and jar when the cylinder 2 comes in contact with the bumper or projection 7 on the cylinder 1. The gasket 11 and the padding 11' are 90 of course provided with openings registering with the ports 10, as more clearly shown in Fig. 3 of the drawings whereby the fluid under pressure after entering the interior of the cylinder 1 by forcing the 95 cylinder 2 upwardly will be permitted to

enter the said port to the interior of the cylinder 2.

The base of the cylinder 2 is provided on its inner face with an integral projection or bumper 12 that forms a seat or the like for the head of the piston. This piston head is removably secured to the lower end of the piston rod 3 and is also provided on its underface with a gasket 14 similar to the gasket 11 and a padding or the like 14' to prevent undue jar when the said piston reaches its lowermost position in contact with the seat or bumper 12. The gaskets 11 and 14 furthermore prevent the leakage 10 of air between the interior of the cylinders and the peripheral edge of the pistons when the same are in operation.

The base of the cylinder 2 projects beyond the wall of the said cylinder and snugly 20 engages the inner walls of the cylinder 1. The gasket 11 which is carried on the underface thereof also has its outer edges bearing against the inner walls of the cylinder 1 as more clearly shown in Fig. 3 of the 25 drawings. The piston head 13 and the gasket 14 of the piston also snugly engage the inner faces of the walls of the cylinder 1 in a similar manner. Hence when the fluid under pressure is introduced to the 30 port 5 and through the conduit 6, the cylinder 2 is adapted to be forced upwardly and when this fluid under pressure enters the interior of the cylinder 1 it will find an exit through the port 10 and base of 35 the cylinder 2, thus permitting the fluid under pressure to enter the interior of the cylinder 2. Entering the cylinder 2, the fluid under pressure will come in contact with the piston head 13 of the rod 3 and 40 will cause the latter to be forced upwardly to carry out the purpose for which this invention is designed.

The cylinder 2 is threaded externally at 45 its upper end and has a threaded cap 15 engaged thereon and the piston rod 3 extends through the said cap member and has a crescent shaped head 16 provided at its upper end for engaging the portion of the device to be raised.

50 We have provided a means for retaining the elements of the device in a raised position and to this end the cylinder 2 is provided with vertically arranged teeth 17 at diametrically opposite points thereon.

55 These teeth form racks on the cylinder and extend for the greater portion of the length of the said cylinder. Slidably supported on the top flange 8 and more particularly within the supporting blocks 18 which are 60 provided with dove-tail cutout portions intermediate their ends are the dove-tailed pawls 18'. These dove-tailed pawls 18' are adapted to fit in the dove-tail cutout portions provided in the blocks 18 and are designed to engage the teeth 17 and retain

the cylinder 2 in an adjusted position. The pawls 18' are provided with slots 19 through which extend pins 20 engaged with the flange 8. These pins 20 retain the pawls 18' in movable position on the flange 8 70 and preferably within the supporting blocks 18.

The outer ends of the pawls 18' are provided with bearings or the like 21 through which extend the arms of an arcuate spring 75 wire member 22. This arcuate spring wire member 22 has its free end slidably supported and extending through suitable staples as shown at 23 in the top flange 8 and the intermediate portion of this arcuate spring member is grouped and bent to provide a handle 24 which extends outwardly beyond the flange 8. A plurality of staples or the like 25 are secured to the flange 8 in the line of an arc and the arms 80 of the spring wire member 22 are disposed thereunder. These staples 25 act as a guide for the arms of the arcuate shaped spring wire member 22 when the same is operated 85 in either direction by the handle 24. 90

The pawls 18' are beveled at their inner engaging end and the teeth 17 on the cylinder 2 are disposed coincident to the bevel of the pawl 17. When it is desired to disengage the pawls from the teeth 17, it is only necessary to force the handle member 24 inwardly and slightly towards the left which action obviously has a tendency to force the arcuate arm of the spring wire member 22 outwardly thus sliding the dove-tail pawls 18' outwardly from the supporting blocks 18 in opposite direction and disengaging the pawls from the teeth 17, whereby the cylinder 2 may be raised or lowered with respect to the cylinder 1, as 95 100 desired. By pushing inwardly upon the spring wire member and moving the same slightly towards the right the pawls 18' will be caused to slide in the blocks 18 and into engagement with the teeth 17 and by providing the blocks 18 and the side faces of the pawls 18' of a dove-tail construction the pawls 18' will be securely held in operative position within the supporting blocks 18 105 and thereby be held in engagement with the 110 teeth 17.

Arranged on the piston 3 for the greater portion of the length thereof and at diametrically opposite sides of the same are the rack teeth 26. Sliding dove-tail pawls 27 115 120 are mounted in supporting blocks provided on the cap plate 15 of the cylinder 2, identical in formation to the supporting blocks and pawls 18' for the purpose of engaging the teeth 26 and retaining the piston rod 3 125 in various adjusted positions. A wire spring member 28 similar to the member 22 is also provided with and has its arcuate shaped arms engaged with the outer bearings formed in the sliding pawls 27 and the 130

free ends of the arms of the arcuate shaped members 28 are slidable in staples on the plate 15 at points designated at 29. These elements designated at 29 are staples 5 of similar construction as those shown at 25 and described above. This member 28 is looped intermediate its ends to form an outstanding handle 30 and by forcing the handle 30 inwardly and slightly to the left 10 or right the pawls 27 are caused to be disengaged or locked in engagement with the teeth 26 in the same manner in which the pawls 18' are held in locked position with relation to the teeth 17 or released therefrom. In this manner the piston rod 3 may 15 be held in various adjusted positions and permitted to be raised and lowered at will. A section of rubber tubing 31 is secured at its lower end to the inlet port 5 and at its 20 opposite end is detachably connected a short section of piping 32. The upper end of the pipe 32 is provided with a threaded nipple 33 for the purpose of permitting the same to be detachably connected to an air supply 25 pump or the like. The pipe 32 is also provided with an extension 34 which is provided with an enlarged head 35 at its outer end and carried therein is a rubber pad 36 having a central opening in registry with 30 the bore in the extension 34.

A hollow stem 37 is threaded at one end to fit in the threaded end of the extension 34 and this stem projects through the rubber pad 36 and into the cap 35. A rotary 35 release valve 38 is carried in the extension 34 intermediate its ends and is of the usual construction. The cap 35 is adapted to be placed on the valve of one of the tires of the vehicle adjacent the jack when the 40 same is in position for lifting purposes and the hollow stem 37 will be caused to come in engagement with the stem found in the usual tire valves and upon depression of the valve stem the air from the tire will pass 45 through the hollow stem 37 and when the valve is turned so as to permit the air to pass through the extension 34 into the pipe 32, the air will then pass through the rubber tubing and into the inlet port 5.

50 From the foregoing description of the construction of our improved fluid pressure jack, the operation thereof will be readily understood and it will be seen that we have provided a simple, inexpensive and efficient 55 means for carrying out the objects of the invention.

Having thus described the invention what we claim as new and desire to secure by Letters Patent is:—

60 1. A pneumatic jack of the class described, comprising an outer cylinder, an inner cylinder, movable vertically with respect to said outer cylinder, means for the admission and control of a fluid pressure to said outer cylinder, a piston including a piston rod 65

movable vertically within said inner cylinder, ratchet teeth arranged vertically on the outer periphery of said inner cylinder at diametrically opposite points thereon, additional ratchet teeth arranged vertically on the piston rod at diametrically opposite points thereon, laterally sliding pawls carried on the outer cylinder adapted for engagement with the teeth of the inner cylinder, additional laterally sliding pawls carried on the inner cylinder adapted for engagement with the teeth of said piston rod, and means for manually controlling the action of said pawls with respect to the teeth on said inner cylinder and piston rod, as and for the purposes described. 70

2. A pneumatic jack of the class described, comprising an outer cylinder, an inner cylinder movable vertically with respect to said outer cylinder, means for the admission and control of a fluid pressure to said outer cylinder, a piston including a piston rod movable vertically within said inner cylinder, ratchet teeth arranged vertically on the outer periphery of said inner cylinder at 80 diametrically opposite points thereon, additional ratchet teeth arranged vertically on the piston rod at diametrically opposite points thereon, laterally sliding pawls mounted on said outer cylinder adapted for engagement with the teeth of said inner cylinder, additional pawls similar to the first mentioned pawls mounted on the inner cylinder adapted for engagement with the teeth of said piston rod, means for manually actuating the first mentioned pawls including an arcuate wire spring member guided on the top of the first mentioned cylinder and having sliding engagement with the outer ends of said pawls, said arcuate wire member being looped and extended intermediate of its ends to form a handle member, and a similar actuating means in connection with the additional pawls. 90

3. A pneumatic jack of the class described, comprising an outer cylinder, an inner cylinder movable vertically with respect to said outer cylinder, means for the admission and control of a fluid pressure to said outer cylinder, a piston including a piston rod movable vertically within said inner cylinder, ratchet teeth arranged vertically on the outer periphery of said inner cylinder at diametrically opposite points thereon, additional ratchet teeth arranged vertically on the piston rod at diametrically opposite points thereon, laterally sliding pawls carried on said outer cylinder adapted for engagement with the teeth of said inner cylinder, the outer ends of said pawls being provided with bearings, additional pawls mounted on the inner cylinder adapted for engagement with the teeth of said piston rod, said additional pawls being also provided with additional bearings at their outer 105 110 115 120 125 130

ends, and means for manually controlling the actuation of the first mentioned pawls comprising an arcuate wire spring member looped intermediate of its ends and extended to form a handle portion, guide members on the top of said outer cylinder through which the arcuate portion of said wire is extended, said wire being also directed through the bearings of said first mentioned pawls and a similar actuating means co-operating with the additional pawls. In testimony whereof I affix my signature.

EUGENE I. POWERS.
HENRY C. HIX.
